UNITED STATES PATENT OFFICE

JOHN P. THURELL, OF FORT MYERS, FLORIDA

SPRINKLER FIRE-PROTECTION APPARATUS

Application filed February 20, 1929. Serial No. 341,474.

The present invention relates to improvements in sprinkler fire protection apparatus, one object of the invention being the provision of a novel arrangement or construction 5 of door and window frames for use in external walls and internal partitions which may be so associated with a sprinkler system and sprinkler head as to assist in directing the sprayed water to extinguish the fire and at the same time produce a "veil" or "mist" in front 10 of the opening of the window or door to prevent flames from passing therethrough.

Another object of the present invention is the provision of a sprinkling system which is 15 equally effective when used in conjunction with city water pressure, a cistern or well water arrangement, or a reservoir upon the roof which may be filled in any desired manner, in combination with a novel type of 20 window and door construction in which the respective sprinklers of automatic type are so housed as to be readily and quickly affected by the rise in temperature due to the effect of fire to automatically release the water and 25 extinguish the flames.

With the foregoing and other objects in view, which will appear as the description proceeds, the invention resides in the combination and arrangements of parts and in the 30 details of construction hereinafter described and claimed, it being understood that changes in the precise embodiment of the invention herein disclosed can be made within the scope of what is claimed without departing from 35 the spirit of the invention.

In the accompanying drawings:—

Figure 1 is a floor plan view of one type of residence with the present sprinkler system in use therewith.

40 Figure 2 is an elevation of the inner side of a two-sash window embodying the present invention.

Figure 3 is an elevation of a door frame and door embodying the present invention.

45 Figure 4 is a view, on a larger scale and partly in section, of the structure shown in Figure 2, showing the detail construction of the same.

Figure 5 is a section taken on line 5—5 of 50 Figure 4.

Figure 6 is a view similar to Figure 4 of the door frame construction.

Figure 7 is a section taken on line 7—7 of Figure 6.

Figure 8 is a section taken on line 8—8 of 55 Figure 2.

Figure 9 is a section taken on line 9—9 of Figure 3.

Figure 10 is an enlarged detail cross-sectional view through one of the automatic 60 sprinkler heads.

Figure 11 is a cross-sectional view through a sprinkler head of chandelier type.

Referring to the drawings, and more particularly to Figure 1 thereof, the numeral 12 designates the outer wall of a building embodying the particular floor plan illustrated in this figure, it being understood, however, that this floor plan is merely illustrative of many that may be used in carrying out the present invention. This floor plan shows the several partition walls 12' which divide the one floor of the building into hallways and 70 rooms.

The numerals 13 and 13' designate, respectively, doorways in the exterior walls 12 and certain of the partitions 12', while the numerals 14 and 14' designate, respectively, double and single window openings in the walls.

Suitably supported above the window and door openings are pipes S through which water is supplied to the sprinklers either from a reservoir (not shown) upon the roof of the house, or through any other means, such as direct connection through automatic valves with the water system. It is also possible that the reservoir may receive water automatically from an individual water plant, the town or municipal plant, or rain-water caught from the roof, and, when desired, the necessary automatic or float valves are employed to regulate the depth of the water therein.

As shown in Figures 2, 4 and 5, the window frame in the opening 14 comprises jambs 19 each forming one wall of a vertical compartment 20 and jambs 22 forming walls of an intermediate hollow column, chamber 23, openings 21 being formed intermediate of the ends of the jambs 19 and openings 24 inter-

mediate the ends of the jambs 22, the purpose of which will presently appear.

A header 25 closes the upper ends of the compartments 20 and the chamber 23 and is provided with openings 26 and 27 which establish communication between these compartments and chamber with an upper compartment or chamber 28 formed above the window frame proper and provided with a header 28'. The outer face 29 of this window frame is provided with an opening 30, the purpose of which will presently appear, while the inner face is formed by the sheet 31 of perforated celluloid or other fusible material, the pipe 15 connected with the sprinkler system being extended into the chamber 28 from above the latter and carrying the globular sprinkler head 16. A fusible plug 17 between the end of the pipe 15 and the sprinkler head normally prevents the passage of water from said pipe to the sprinkler head.

In the interior door construction, the frame 13' is provided, as shown in Figures 3, 6 and 7, with a header 33 which, with the sub-header 32, provides a chamber 34. Openings 35, formed in the door jambs between the header 33 and sub-header 32 are directed toward the wall or partition in which the frame 13' is supported. The front and rear of the chamber 34 are closed by perforated sheets of celluloid or other fusible material. A sprinkler head 16', connected by a pipe 15 to the pipe S, is mounted in the chamber 34.

In the case of a doorway in an outer wall of the building, only the inner side of the chamber 34 is closed by a perforated fusible sheet and the other side of the chamber is closed by a plate, such as the plate 29, shown in Figure 8, having an opening 30. In freezing weather the sprinkler heads 16 and 16' may be isolated from the water supply pipe S by a valve (not shown).

Where so desired, a sprinkler 16^a may be mounted centrally of the room and within the support 38 which, in turn, supports the sheet metal member 39 constituting the upper supporting fixture of an electric chandelier 40, or the like, the same being provided with perforation 41 through which water will be projected from the automatic sprinkler 16^a when the plug 17 is fused by excessive heat.

Although one form of sprinkler head is here shown, it will be apparent that any type of automatic heat released sprinkler head may be employed without departing from the spirit of the present invention.

In operation, the reservoir (not shown) supplies water to the various sprinklers throughout the entire system, and should draperies, or the like, become ignited, the heat therefrom at any of the windows will cause the celluloid sheet 31 to fuse, and such heat will also fuse the plug 17 so that water will be projected into the chamber 28 and through the various openings therein downwardly

through the compartments and chambers of the frame and outwardly through the openings 26' into the walls or the space within the wall, thus extinguishing the flames and at the same time preventing the passage of flames through the window.

The sprinkler heads 16' in the door frames operate in the same fashion as those in the window frames.

Where so desired, the outer and inner walls or partitions of the building may each have a concrete base and all the walls may be constructed of a fire-resisting material, in which event, the only inflammable materials employed would be those in the door and window frames. Thus fire adjacent the doors or windows will ignite the ignitable sheets 36 and 37 and fuse the plug 17 so that water may flow through the sprinklers.

I claim:—

1. In a building having door and window openings in its walls and door openings in its partitions, frames in said door and window openings each having a chamber at its upper portion, a sprinkler head of the heat responsive type in each of said chambers, means for supplying a fire-extinguishing agent to said sprinkler heads, and panels closing the sides of said chambers, one of the panels of each of said chambers being formed of inflammable material and being so positioned relatively to said sprinkler heads that their burning will release said heads.

2. A frame for an opening in a wall or partition of a building having a hollow portion behind each of its jambs and a chamber above its head communicating with said hollow portions, a sprinkler head in said chamber having an inlet for connection to a fire-extinguishing-agent supply means, a fusible plug in said inlet, and a perforated panel of inflammable material closing said chamber and so positioned relatively to said sprinkler head that its burning will fuse said plug.

3. A frame for an opening in a wall or partition of a building comprising a head, a pair of jambs, and a sub-head between said jambs below said head, said jambs, head and sub-head forming a chamber and said jambs having openings therethrough between said head and sub-head, means closing said chamber at one of its sides, a panel of inflammable material closing the other side of said chamber, and a sprinkler head of the heat responsive type in said chamber, said sprinkler head having means for connection to a fire extinguishing agent supply means and being releasable by the burning of said inflammable panel.

4. A frame for an opening in a wall of a building comprising a plurality of hollow pedestals and a chamber above said pedestals, said chamber having passageways in its bottom wall communicating with the interiors of said pedestals and also having passageways in

its end walls, panels closing the sides of said chamber, one of which panels is formed of inflammable material, and a sprinkler head of the heat responsive type in said chamber,
5 said sprinkler head being releasable by the burning of said inflammable panel.

In testimony whereof I have hereunto set
my hand.

JOHN P. THURELL.
